UNITED STATES PATENT OFFICE

EDUARD SCHIEGRIES AND PAUL ISCHEBECK, OF DUISBURG-MEIDERICH, GERMANY, AS
SIGNORS TO THE FIRM VEREINIGTE STAHLWERKE AKTIENGESELLSCHAFT, OF DUS-
SELDORF, GERMANY

APPARATUS FOR MOVING TAMPING MACHINES

Application filed January 29, 1931, Serial No. 512,227, and in Germany October 28, 1930.

The object of the present invention is to provide an arrangement adapted to guide tamping machines in front of the tap hole to be stopped. The operation of guiding 5 tamping machines in front of the tap hole of furnaces is at the present time usually done by hand. In this case the machine is suspended from a rotatably swinging arm. It is evident that this work is not without danger 10 to the operator who must guide the machine until it is in position in front of the tapping groove, and then bring it into the necessary gradient and in this position press it securely against the tap hole until the machine is 15 securely held in front of the said tap hole by the actuation of two holding claws. Taking into consideration the extent of the danger connected with this work it is evident that during its execution, the outflow of molten metal 20 or molten slag from the furnace cannot be interrupted, and also the difficulty experienced owing to the weight of the machine and the heat emitted by the molten metal or molten slag one cannot always succeed in 25 bringing the machine into the required position in front of the tap hole. This inconvenience therefore often leads to considerable interruption in the work which, as a consequence, entails great expense. 30 Automatically operated introduction is already known for tap hole stopping machines, but this known arrangement is however very complicated and the amount of space required is disproportionately large. 35 The object of the present invention is to overcome these disadvantages and also to provide a machine which does not have to be guided in front of the tap hole by hand, and also to ensure the correct positioning of the 40 machine in front of the tap hole.

The accompanying drawings show one form of apparatus made in accordance with the present invention, Figure 1 being a side elevation, Figure 2 a top plan, Figure 3 a 45 side view, Fig. 4 is a top plan view showing the parts in shifted position. Fig. 5 is a plan view of the crank handle guide plate. Fig. 6 is a detail view showing the crank and plate engaged. Figs. 7 and 8 are fragmentary detail views.

In these drawings the tamping machine is carried by a structure comprising an arm mounted on a vertical column 1 rotatable about its vertical axis and suspended from the said arm by an arrangement described below more in detail. A rocking shaft 2 is mounted in bearings 3 and 3' on a swinging arm 4 on the column 1 at one end of which is carried a member for the suspension of the tamping machine. The other end of the shaft is extended beyond the rotatable column of the swinging arm and provided with a crank. The crank handle 5 of the crank extends through a guide slot 6 in the fixed metal plate 7. On the swinging arm a guide parallelogram 8 is situated, the sides of which lie in a horizontal plane. This parallelogram is formed as follows:—The central point of the transverse member *a* is situated most advantageously as if in the rotating axis 55 of the swinging arm and said member is rigidly fixed so that its direction runs preferably parallel to the tapping groove. Its direction can, however be altered, for example, by a hand operated feed screw 10. The two side members *b* and *c* extend approximately to the end of the rocking shaft 2 and are linked to or pivotally mounted at the ends 60 of the transverse member *a*.

The opposite ends of the side members *b* and *c* are also pivotally connected or linked to the transverse member *d* which is provided with two symmetrically arranged guide slots. 65

The suspension arrangement of the tamping machine is such that, with the tamping machine itself as a fourth side forms a parallelogram. One side of this parallelogram is the transverse member *e*, which is provided with a long central hole or slot and is pushed upon the one end of the rocking shaft by means of a bolt fastened to this, for example in the manner of a Cardan link or universal joint. The other two vertical members *f* and *g* extending from the ends of the transverse 70 member *e* of the parallelogram pass perpendicularly through the guide slot of the transverse member *d* of the parallelogram. The tamping machine itself is suspended from the ends of the vertical members *f* and *g*. 75

In Figures 2 and 3 the machine is shown in operative position by dotted lines.

The operation of the machine is as follows:—The post 1 is swung about its axis by an air operated cylinder 9. The transverse member *d* of the guide parallelogram 8 is moved parallel to the side *a*. By this means the transverse member *d* of the guide parallelogram co-operates with the vertical members *f* and *g* passing through its slots and carrying the tamping machine. The transverse member *e* by means of the slot or hole provided therein is pushed along the rocking shaft 2 and thus is able to rock and adapt itself to the required lateral displacement owing to the transverse member *d* changing its position. The gradient or dip of the tamping machine to the tap hole is attained, during the execution of these movements, by means of the crank handle 5 moving in the inclined or curved guide slot 6 in the metal plate 7. The inclination of the guide slot is adjustable; that is, its gradient is dependent upon the intended gradient of the tamping machine to the tap hole. When the swinging arm and with it the shaft 2, swings round, the crank handle 5 of the crank shaft follows the course of the guide slot 6 in the plate 7, thus the rocking shaft 2 is rotated according to the gradient of the slot and with it also the transverse member *e* and consequently the tamping machine linked to or pivoted at the lower end of the vertical rods *f* and *g* dips.

35. We claim:

1. Apparatus for moving tamping machines to and from the operative position in the furnace tap hole, comprising means for moving the tamping machine parallel to itself horizontally and means for inclining it in the vertical plane, the means for inclining the tamping machine in the vertical plane being operated automatically by the means for moving it horizontally.

45. 2. Apparatus for moving tamping machines to and from the operative position in the furnace tap hole, comprising a series of members linked together to form a parallelogram of a parallel motion, a supporting structure, a vertical column forming an upright member of said structure and rotatable about its vertical axis, means for suspending the parallel motion horizontally from the said structure, means for supporting the tamping machine from the structure independently of the parallel motion and means for inclining it in the vertical plane, the means for inclining the tamping machine in the vertical plane being operated automatically by the means for moving it horizontally.

55. 3. Apparatus for moving tamping machines to and from the operative position in the furnace tap hole, comprising a series of members linked together to form a parallelogram of a parallel motion, a supporting struc-

ture, a vertical column forming an upright member of said structure and rotatable about its vertical axis, means for suspending the parallel motion horizontally from the said structure, a vertical parallel motion, the tamping machine being supported from the said structure by the members of the vertical parallel motion and means for inclining it in the vertical plane, the means for inclining the tamping machine in the vertical plane being operated automatically by the means for moving it horizontally.

4. Apparatus for moving tamping machines to and from the operative position in the furnace tap hole, comprising a series of members linked together to form a parallelogram of a parallel motion, a supporting structure, a vertical column forming an upright member of said structure and rotatable about its vertical axis, means for suspending the parallel motion horizontally from the said structure, a horizontal transverse member pivotally mounted on the supporting structure so as to rock about its central pivot in the vertical plane, the tamping machine being supported by two vertical rods pivoted thereto at their lower ends, and pivoted at their upper ends to the horizontal transverse member, the disposition of the pivots being arranged to form a vertical parallel movement, and means for inclining it in the vertical plane, the means for inclining the tamping machine in the vertical plane being operated automatically by the means for moving it horizontally.

5. Apparatus for moving tamping machines to and from the operative position in the furnace tap hole, comprising a series of members linked together to form a parallelogram of a parallel motion, a supporting structure, a vertical column forming an upright member of the said structure and rotatable about its vertical axis, a transverse member, a horizontal rocking shaft and bearings for supporting the same on the structure, the transverse shaft being rockable transversely about its central pivot by the horizontal rocking shaft, means for suspending the parallel motion horizontally from the structure, means for supporting the tamping machine from the structure independently of the parallel motion, two vertical members pivoted at their lower ends to the tamping machine and at their upper ends to the opposite ends of the transverse member, a crank fixed on an end of the horizontal rocking shaft, a fixed metal plate having an inclined guide slot therein, the crank handle of the rocking shaft extending into the slot of the slotted plate, so that as the structure is turned about its vertical column a turning movement is also imparted to the transverse member from the ends of which the vertical rods carrying the tamping machine are suspended.

chines to and from the operative position in the furnace tap hole, comprising a series of members linked together to form a parallelogram of a parallel motion, a supporting structure, a vertical column forming an upright member of said structure and rotatable about its vertical axis, means for suspending the parallel motion horizontally from the said structure, a horizontal transverse member 5 pivotally mounted on the supporting structure so as to rock about its central pivot in a vertical plane, the tamping machine being supported by two vertical rods pivoted thereto at their lower ends, and pivoted at their 10 upper ends to the horizontal transverse member, the disposition of the pivots being arranged to form a vertical parallel movement and means for inclining it in the vertical plane, the means for inclining the tamping 15 machine in the vertical plane being operated automatically by the means for moving it horizontally, the front member of the horizontal parallel motion being slotted vertically and the vertical members of the 20 vertical parallel motion passing freely through the slots of the slotted member of the parallel motion.

7. Apparatus for moving tamping machines to and from the operative position in 30 the furnace tap hole, comprising a series of members linked together to form the parallelogram of a parallel motion, a supporting structure, a vertical column forming an upright member of the said structure and rotatable about its vertical axis, a transverse member, a horizontal rocking shaft and means for supporting the same on the structure, a universal joint, the transverse member being fixed on the rockable horizontal shaft, 35 means for suspending the parallel motion horizontally from the structure, means for supporting the tamping machine from the structure independently of the parallel motion, two vertical members pivoted at their 40 lower ends to the tamping machine and at their upper ends to the opposite ends of the transverse member, a crank fixed on the ends of the horizontal rocking shaft, a fixed metal plate having an inclined guide slot therein, 45 the crank handle of the rocking shaft extending into the slot of the slotted plate, so that as the structure is turned about its vertical column a turning movement is also imparted to the transverse member from the 50 ends of which the vertical rods carrying the tamping machine are suspended.
